LOCATING BOTTOM OF OIL PRODUCTION

Daniel Silverman, Tulsa, Okla., assignor to Standard Oil and Gas Company, Tulsa, Okla., a corporation of Delaware

Application January 14, 1942, Serial No. 426,714

5 Claims. (Cl. 175—182)

This invention pertains to the art of determining the location of regions of entry of oil or similar non-conducting fluids into a well producing the same. More particularly this invention pertains to the determination of the lowest point of oil entry into an oil or gas well, particularly when such well is producing salt water as well as oil.

In the production of oil or other non-conducting liquids from a well it often happens that the well taps a source of a conducting liquid such as salt water or the like, so that the production obtained is a mixture of the two liquids. Obviously it is highly desirable to eliminate, as far as can be, the production of the undesired liquid. After the points of water entry have been determined by one means or another various cementing methods are used to stop entry of the water into the well. If the points of entry of the oil and the salt water are widely separated the problem is a simple one. Generally the points of entry of each fluid are only approximately known and quite often they are immediately adjacent so that often the flow of oil is affected by operations tending to cut down the flow of water.

It is an object of this invention to provide a method for determining the location of the lowest point of entry of the oil so that by comparison with the data on the location of the points of entry of water a decision can be made as to the feasibility of trying to reduce the water without affecting the oil. It is a further object of this invention to provide means whereby the lowest point of oil entry into a well can be determined accurately, rapidly, and without the use of complicated equipment in the well.

In some instances it is desirable to know the location of the point of entry of the oil in a well in which no salt water is present. It is an object of this invention to provide a method and means for determining the point of oil entry in such instances. Further objects and advantages of this invention will be apparent from a perusal of the accompanying specification.

In order to illustrate the invention several drawings accompany this specification and form a part thereof. They illustrate one simple embodiment of the invention. There is no intent to limit the scope of the invention to the apparatus illustrated and described. In these figures the same reference numeral in several figures refers to the same or a corresponding part.

In these drawings, Figure 1 represents in diagrammatic form a cross section of a well penetrating earth formations including at least one oil

bearing formation, together with apparatus useful in carrying out this invention;

Figure 2 is a diagrammatic representation of a portion of the well and the formations shown in Figure 1, illustrating a later step in the testing procedure;

Figure 3 is a representation of a chart obtained by use of the apparatus shown in Figure 1.

In brief this method might be described as stopping the flow of well fluids into the well, displacing all of the fluids in the well to a point above the suspected region of entry of the oil by a relatively non-conducting liquid, the density of which exceeds that of the salt water in the well, and which is miscible with the oil in the well, thereafter causing well fluids to flow into the well, stopping the flow of the fluids into the well to produce a period of quiescence during which the water which has been produced (or added if the well does not produce salt water) settles to form an interface defining the lowest point of entry of the oil, and measuring during the period of quiescence the conductivity of the liquids in the well as a function of depth in order to determine this interface.

This is illustrated in part by Figure 1. In this figure a well indicated generally at 11 has been drilled from the surface of the earth 12, penetrating formations 13 to 16. Of these formations 14 is assumed to be an oil producing formation and 16 is assumed to be a water producing formation. As will be apparent from further discussion it is not necessary that these formations occupy the relative positions shown. Casing 17 has been cemented by cement 18 into the well down to a certain point in the relatively impervious formation 13. Below this point the walls of the well are uncased and form the producing region of the well. Tubing 19 has been set in the well and held in place by a casing head 20 which is firmly attached to the top of the casing 17. Valved lines 21 and 22 form a means of access to the annular space between the casing 17 and the tubing 19. The upper end of the tubing itself terminates in a cross 23, one arm of which is closed by a valved line 24, the second arm of which can be closed by a plug 25, and the third arm of which, during the testing period, is closed by a stuffing box 26. Normally a plug would be used during the time that the testing is not carried on.

For the purpose of this discussion it is assumed that the energy in the well formation is still sufficient to cause the well to flow when the valve 24 is opened. It is to be understood, however, that the system of testing employed is not limited in its

application to use in this kind of a well, but that it can be used to equal advantage in the testing of a well which has passed its flowing life and which is either pumped or produced by gas lift or the like.

As a first step in the preparation of the well for the test the plug normally closing the top of cross 23 is replaced by the stuffing box 26. The valves in lines 21, 22, and 24 are then closed, stopping the flow of well fluids into the well. A cable 27 is passed through the stuffing box 26 and lowered into the well until the two electrodes 28 and 29 are in the vicinity of the uncased portion of the well. This cable 27 contains at least two conductors which are insulated from each other. Thus, for example, it may consist of a single central conductor surrounded by a sheath of insulation which in turn is surrounded by an outer metallic sheath forming the second conductor, or two insulated conductors surrounded by a non-metallic sheath may be used if desired. Also a greater number of conductors can be used, although this is normally not desirable. Each of the two conductors is separately connected to one of the two electrodes 28 or 29 so that these electrodes can be connected through the cable to apparatus at the top of the well.

At the top of the well the conductors are connected to a battery 30 or other source of potential and a resistor 31 completing the circuit. Normally the cable 27 is carried upon a reel in a manner well known in the art with the ends of the conductors brought out to slip rings on the reel against which brushes connected to the battery 30 and the resistor 31 are connected. The circuit including the two electrodes 28 and 29 is arranged in such a fashion that the flow of electricity through the resistor 31 depends upon the conductivity of the fluid between the two electrodes. The drop of voltage across this resistor 31 therefore increases as the conductivity between the electrodes increases and vice versa. Normally the electrodes 28 and 29 are spaced relatively closely together, of the order of 3 to 12 inches apart. However, closer spacing of the order of an inch or less, or wider spacing up to the order of several feet may be used if desired.

Preferably after the electrodes have been placed in the encased portion of the well, but not necessarily so, a conditioning liquid is pumped into the well. This conditioning liquid should be at least a fair electrical insulator and miscible with the well fluid which is to be located, but which is immiscible with water. Organic liquids such as carbon tetrachloride, carbon disulfide, chloroform, bromoform, the trichlor and tetrachlor ethylenes, and the corresponding bromine compounds, etc., are usable in this connection. The liquid must be one which is heavier than salt water. Mixtures of such materials with other lighter liquids can be employed. Thus, for example, I prefer to use a mixture of carbon disulfide or carbon tetrachloride with a petroleum oil in such proportions that the density of the resultant liquid is slightly heavier than that of the salt water in the well, that is, so that the specific gravity of the liquid exceeds that of salt water but by not more than about 30% maximum. This liquid is pumped into the well through any of the valved lines 21, 23 or 24. Because it is of greater density than that of the fluids in the well, it sinks to the bottom and displaces the well fluids above it. If desired the liquid can be introduced into the well by means of a dump bailer or any other means of introducing a

liquid into a well known in the art. An interface 32 between this liquid and the well fluids is formed. Enough of the liquid should be used to insure that all of the well fluids have been displaced above the region in which it is expected that oil is present. This can be secured by pumping in a sufficient volume of the conditioning liquid to fill the uncased portion of the well. If the specific gravity is kept to a value which is only slightly greater than that of the salt water in the well, it is apparent that the hydrostatic head of the liquids in the well will be almost the same as that which existed before the conditioning liquid was pumped in so that there will be little tendency for this conditioning liquid to leak into the permeable formations and thus be lost. After the well fluids have been displaced to a point above the region of ingress by this non-conducting high density liquid, the well is caused to flow (at a relatively low rate preferably) by opening one of the valved lines 21, 22 and 24. This causes the various well fluids to flow through the conditioning liquid present up past the interface 32 between the well fluids and the conditioning liquid, due to the low specific gravity of these well fluids relative to that of the conditioning liquid. Since the salt water is relatively immiscible with the conditioning liquid, there will be little effect on this liquid due to the passage of the salt water. On the other hand the oil which is flowing through the liquid is miscible with it, and therefore dilutes the conditioning liquid. This dilution continues as long as the flow exists and extends upward from the lowest point of oil ingress into the well. Since the specific gravity of oil is less than that of water the specific gravity of the diluted conditioning fluid decreases until it is less than that of the salt water. The operator causes the well fluids to flow into the well until he is sure that the well conditioning liquid above the point of lowest oil entry has been diluted to such a point that the specific gravity is less than that of the salt water. Production from the well is then stopped by closing the valve 45 which has been opened, causing the flow of the fluid from the permeable formations into the uncased portion of the well to cease. This flow is stopped for an appreciable period of quiescence. During this time the salt water in the well which is of greater specific gravity than the diluted conditioning liquid will displace this diluted conditioning liquid by gravitation and thus form an interface 33 (Figure 2) with the non-diluted conditioning liquid at the lowest point at which the dilution has occurred. Such period depends upon the relative densities of the diluted conditioning fluid, and the salt water, and must be, of course, sufficiently long to permit the salt water substantially completely to replace the diluted conditioning liquid under the influence of the force of gravity. Accordingly, the time required for this appreciable period of quiescence cannot be specifically given in terms of minutes or hours but preferably the time should exceed the order of 20 minutes. The longer this appreciable period of quiescence, the more certain is the gravitational separation. On the other hand, excessive periods of quiescence, such as the order of 8 hours or more, will normally give erroneous results in that there is sufficient time to permit some of the undiluted conditioning fluid to settle into the formations adjacent the well. This obviously is the lowest point of oil entry into the well. It is apparent that it makes no difference whether the salt water in the well was produced

from the bottom bed 16 or from a bed lying above the oil stratum in so far as the formation of the interface 33 is concerned, because whether the salt water was below or above the point of oil entry, during the period of quiescence the salt water must inevitably come to rest at a level corresponding to this lowest point of oil entry.

The operator now prepares to locate the position of this interface.

In order to accomplish this result a recording voltmeter or the like is connected across the resistor 31. In Figure 1, one such type of recording voltmeter is shown. In this figure the drop across resistance 31 is applied between the grid and cathode of a vacuum tube 34. The filament of this tube is energized by a storage battery or other suitable supply of potential which is connected across the points x-x. A suitable biasing resistor 35 is employed. The plate of this vacuum tube 34 is connected through a plate resistance 36 to a battery 37 or other source of direct potential which is in turn connected to the cathode of vacuum tube 34. In order that the steady plate current of the vacuum tube 34 need not affect the reading of the recording voltmeter, a second vacuum tube circuit is employed. This includes a vacuum tube 38 preferably of the same type as that of vacuum tube 34, the cathode of which is connected to the cathode of the vacuum tube 34 through a variable resistance 39. The grid of this tube 38 can also be connected to the cathode of the vacuum tube 34. The plate of tube 38 is connected through a resistance 40, which preferably is of the same size as resistance 36, to the positive side of battery 37. A recording milliammeter 41 or the like is connected across the plates of the two tubes 34 and 38.

Prior to operation, with no drop of potential across the resistance 31, resistor 39 is adjusted so that the drop of potential across resistance 40 is equal to the drop of potential across resistance 36 so that the voltmeter 41 reads zero. The equipment is now set to operate.

The electrodes 28 and 29 are lowered through the uncased portion of the well and the recording milliammeter records on a moving chart 42, the amplified drop of potential across the resistance 31. As soon as the electrodes 28 and 29 are immersed in the salt water there will be a large drop of potential across the resistance 31 and a corresponding deflection of the recording voltmeter 41. However, as soon as the electrodes pass the interface 33 they pass into the relatively high resistance conditioning liquid which has been placed in the well, and the flow of current through resistance 31 abruptly decreases, thus decreasing the corresponding deflection of the voltmeter 41. The resultant chart will appear approximately as shown in Figure 3 with a large change in deflection at the point A which corresponds to the point at which the electrodes passed the interface 33 between the conducting brine in the well and the relatively non-conducting conditioning liquid. A record is made of the movement of the chart 41 as the depth of the electrodes 28 and 29 is varied in the well, in a manner well known in the well logging art. Therefore it is possible to correlate the point at which the deflection changed abruptly with the elevation of the electrodes in the well at that instant. By this means the position of the interface 33 can be accurately determined. The location of the interface concludes the test. The well can then be put back on production, or steps taken to isolate the water, etc.

It is not particularly essential that the type of system described above be used to determine the point at which the conductivity of the liquids in the well changes as the interface 33 is passed.

5 Any type of conductivity determining apparatus known in the prior art can be used for this purpose.

It is occasionally found that if particular care is not used in employing a conditioning liquid the 10 specific gravity of which is very close to that of the brine in the well, that a certain amount of the liquid will leak into the formations, causing difficulty in determining the location of the interface 33. In such cases it is advantageous to 15 reduce the permeability of the formations at the point at which they form the walls of the well by circulating into the well drilling fluid or an aqueous suspension of bentonite or the like which is pumped into the well through one of the valved lines in the tubing or casing and pumped out through the other line, for example, in through line 22 and out through line 24. By this means a filter cake is built up on the walls of the well thus decreasing the permeability of the formations and tending to stop the flow of the conditioning liquid into the well formations. This reduction of permeability is carried out before the well is conditioned with the high resistivity conditioning liquid, as previously described. It should be emphasized, however, that the filter cake which is built up does not, of course, decrease the permeability of the formations to zero, that is, it does not seal off the well formations from the well. On the other hand this does not affect 20 the result of the test if sufficient time is allowed to elapse so that the well fluids can seep into the well while the early steps of this procedure are being carried out.

40 If the well has passed through the flowing period and is either on the pump or being produced by gas lift, the same type of procedure is carried on with the exception that in this case instead of opening a valve at the surface in order to cause the formation fluids to flow into the well it is necessary to pump some of the well fluids out of the well or to gas lift these materials. This is the only change in the test technique which need be employed in order to carry out the invention in that type of well. If there is no salt water produced naturally in the well, salt water can be pumped into the well after the conditioning liquid has been placed. The procedure is otherwise as previously described.

45 Various changes and modifications of the apparatus used in determining the location of the interface can be employed. Other variations in the entire testing technique will be apparent to those skilled in the art. The invention is not limited to the particular embodiment described 50 but is best set out in the appended claims.

I claim:

1. A method of determining the lowest region of entry of a relatively non-conducting liquid less dense than water into a well, comprising stopping the flow of well fluids including salt water into said well, displacing said well fluids in said well to a point above said region of entry by a conditioning liquid which is immiscible with water and miscible with said relatively non-conducting liquid, and an electrical characteristic of which is markedly different from that of salt water, the density of said conditioning liquid exceeding that of the salt water in the well, and the density of said conditioning liquid when sufficiently diluted with said relatively non-conducting liquid being

less than that of said salt water, causing the flow of well fluids into said well for such time that a portion of said conditioning liquid will be diluted with said relatively non-conducting liquid and will have a density less than that of said salt water, again stopping the flow of said well fluids into said well to establish a substantial period of quiescence sufficient to permit replacement of diluted conditioning liquid by salt water from said well fluids, whereby an interface is formed between said salt water and the undiluted portion of said conditioning liquid, and measuring after said period of quiescence the electrical characteristic of the liquid materials in said well as a function of depth.

2. A method of determining the lowest region of entry of oil into an oil well, comprising stopping the flow of well fluids including salt water into said well, displacing said well fluids in said well to a point above said region of entry by a relatively non-conducting liquid which is immiscible with water and miscible with oil, the density of said liquid exceeding that of the salt water in the well, and the density of said liquid when sufficiently diluted with oil being less than that of said salt water, causing the flow of well fluids into said well, whereby oil and salt water flow into said well and said oil will dilute a portion of said non-conducting liquid until the density is less than that of said salt water, again stopping the flow of said well fluids into said well to establish a substantial period of quiescence sufficient to permit replacement of diluted non-conducting liquid by salt water from said well fluids whereby an interface is formed between said salt water and the undiluted portion of said non-conducting liquid and measuring after said period of quiescence the conductivity of the liquid materials in said well as a function of depth.

3. A method of determining the lowest region of entry of oil into an oil well, which also produces salt water comprising stopping the flow of well fluids into said well, displacing said well fluids in said well to a point above said region of entry by a high resistivity liquid which is immiscible with water and miscible with oil, the density of said high resistivity liquid exceeding that of the salt water in the well, and the density of said liquid when sufficiently diluted with oil being less than that of said salt water, causing the flow of oil and salt water into said well from the surrounding formations for such time that a portion of said high resistivity liquid will be diluted with oil and will have a density less than that of said salt water, again stopping the flow of said well fluids into said well to establish a substantial period of quiescence sufficient to permit gravitational replacement of diluted high resistivity liquid by salt water from said well fluids, whereby an interface is formed between said salt water and the undiluted portion of the high resistivity

liquid and measuring at the end of said period of quiescence the conductivity of the liquids in said well as a function of depth, whereby the position of said interface is determined.

- 5 4. A method of determining the lowest region of entry of oil into an oil well, which also produces salt water comprising stopping the flow of well fluids into said well, displacing said well fluids in said well to a point above said region of entry by a high resistivity, water immiscible heavy solvent for oil, the density of which is greater than that of the salt water in the well and the density of said solvent when sufficiently diluted with oil being less than that of said salt water, causing the flow of oil and salt water into said well from the surrounding formations for such time that the solvent will be diluted with oil and will have a density less than that of said salt water, again stopping the flow of said well fluids into said well to establish a period of quiescence sufficient to permit gravitational replacement of diluted solvent by salt water from said well fluids, whereby an interface is formed between said salt water and the undiluted high resistivity solvent and measuring and recording after completion of said gravitational replacement a function of the resistance between two electrodes lowered through the liquids in said well, from which the position of said interface is determined.
- 10 20 25 30 35 40 45 50 55 60
5. A method of determining the lowest region of entry of oil into a well also producing salt water which comprises decreasing the permeability of the walls of said well in the uncased portions thereof, stopping the flow of well fluids into said well, displacing said well fluids in said well to a point above said region of entry by a high resistivity liquid, the specific gravity of which is greater than that of the salt water in the well, but less than 1.3, said high resistivity liquid being immiscible with water and miscible with oil, and the specific gravity of said liquid when sufficiently diluted with oil being less than that of said salt water, causing the flow of oil and salt water into said well from the surrounding formations for a period of time sufficient to permit a portion of said liquid to be diluted with oil and have a specific gravity less than that of said salt water, again stopping the flow of said well fluids into said well to establish a substantial period of quiescence sufficient to permit gravitational replacement of diluted liquid by said salt water from said well fluids, whereby an interface is formed between said salt water and the undiluted liquid, and measuring after said period of quiescence and after the substantially complete gravitational replacement of said diluted liquid, the conductivity of the liquids in said well as a function of depth, whereby the position of said interface can be determined.

DANIEL SILVERMAN.
